INFLATING MEANS

Walter J. Phane, Akron, Ohio, assignor to Wingfoot Corporation, Akron, Ohio, a corporation of Delaware

Application March 7, 1951, Serial No. 214,355

6 Claims. (Cl. 150—9)

1

The present invention relates to an improved form of inflating means for an inflatable fabric member. More particularly, the present invention pertains to an inflating element or valve for use on any of several different forms of inflatable fabric products including a wide variety of structural shapes such, for example, as boats, pontoon boats, buildings, forms, and other similar articles.

The inflating means of the present invention is especially well adapted to use in connection with such inflatable articles as are capable of fabrication from a double-ply fabric.

This double-ply fabric embodies a top ply and bottom ply disposed in substantially superposed relation to each other with a multiplicity of substantially inextensible tie threads of predetermined length extending therebetween and woven at least partially into each of the plies.

The various products, when made from this double-ply fabric, are cut and formed in much the same fashion as the conventional inflatable structure formed from single-ply fabric. When the fabric parts are shaped, the ends and edges sealed and finally treated with a fluid-impervious coating, they are inflated through any suitable form of inflating tube or valve structure through which fluid under pressure may be introduced to the chamber defined by and enclosed within the cooperating top and bottom plies of the double-ply fabric.

The double-ply fabric, however, unlike the single-ply material previously used, must have the various fittings which are employed therewith firmly anchored into both plies to prevent destruction of the fabric when it is finally sealed and inflated. This is attributable to the fact that when an opening for insertion of a valve, for example, is cut in one ply of the double-ply fabric, the tie threads in the area immediately adjacent the cut are left unanchored in the remaining ply. This places an excessive strain on the other tie threads in the fabric element adjacent the portion removed when the element is sealed and inflated.

The inflating means of the present invention was developed for the express purpose of providing a positive reinforcement in the area where the fluid is admitted to the fabric element and to prevent failure of the double-ply fabric. It is highly advantageous in that it enables the distribution of the stresses created in the double-ply fabric by the inflation of the structure to be distributed and thus to prevent failures caused by the breaking or disengagement of the unanchored tie threads in the fabric.

2

It is the primary object of the present invention to provide an inflating means which is particularly adapted to use in connection with structures fabricated from double-ply fabric.

It is another object of the present invention to provide an improved form of inflating means which is capable of use with products manufactured from double-ply fabric for preventing failure of the fabric in the area where the inflating means is installed.

Other features and advantages of the present invention will become apparent as the description of one form of inflating means embodying the inventive concept proceeds.

15 In the drawing, Fig. 1 represents a partial plan view of a double-ply fabric element with an inflating means embodying the teachings of the present invention. Fig. 2 is a vertical cross-section taken substantially along the line 2—2 in Fig. 1 with parts in elevation and broken away. Fig. 3 is an enlarged detail in horizontal section of a portion of the conduit for the inflating means.

The reference numeral 1 in Figs. 1 and 2 identifies the inflating means of the present invention generally. One of the principal components of the inflating means 1 is an inflating element or valve 2 having a threaded end portion 3 housing a conventional valve core 4 internally of its bore 5. The valve 2 comprises a rubber stem portion 6 and an integrally formed flange portion 7. It will be readily understood that any conventional form of valve stem, whether it be of all rubber or all metal construction, will suffice for the purposes of the present invention, the one shown here being solely for the purpose of illustration.

20 The valve 2 is disposed with its integral flange portion 7 in registration with an aperture 8 in an inflatable fabric member or segment 9. The inflatable fabric member 9 comprises a top fabric ply 11 which is disposed in opposed relation to a bottom fabric ply 12 and secured thereto by means of a multiplicity of tie threads 13. The tie threads 13 are of predetermined length and 25 are substantially inextensible, whereby the spacing between the top fabric ply 11 and the bottom fabric ply 12 is predetermined when the inflatable fabric member 9 is satisfactorily sealed and inflated.

20 In the use of an inflatable fabric member 9 in various types of construction to which it is adapted, the outermost surfaces of the top fabric ply 11 and the bottom fabric ply 12 are coated 55 with a suitable fluid-impervious coating such, for

example, as a thin coating of rubber or the like. It will be understood that when the inflatable fabric member 9 is sealed and inflated, the top fabric ply 11 and the bottom fabric ply 12 will be disposed in the relationship illustrated in Fig. 2. When the inflatable fabric member is void of inflating fluid, the top fabric ply 11 will ordinarily be disposed in opposed contacting relation with the bottom fabric ply 12, thereby rendering the structure readily collapsible.

The aperture 8 in the inflatable fabric member 9 is defined by a fabric sleeve 10 of generally tubular shape forming a conduit. This conduit 10 may take any suitable shape, being either circular, square, or rectangular in cross-section. The conduit 10 serves to provide a satisfactory reinforcement for the aperture 8 to hold the top fabric ply 11 and the bottom fabric ply 12 in predetermined spaced relation as determined by the length of the tie threads 13.

The conduit 10 is preferably of generally cylindrical shape by reason of its ease of construction. As illustrated in Fig. 3 of the drawing, a piece of single-ply fabric 14 is formed into the cylindrical sleeve 10 with its ends lapped over to form the joint 15 and bonded together. An inner and outer tape reinforcement 16 and 17, respectively, serve to protect and reinforce the joint 15.

The piece of fabric 14 forming the sleeve 10 is provided with a flanged portion 18 which is formed by folding back a portion of the end of the fabric 14 and slitting the same to form a series of tabs 19 which are disposed in contact with the top fabric ply 11 to which they are secured by a suitable bonding agent. The opposite end of the piece of fabric 14 comprising the sleeve 10 is treated in a similar manner to form the flange portion 20 comprising a series of tabs 21 corresponding generally to the several tabs 19 formed in the flanged portion 18 just described. As before, the several tabs 21 are adhesively secured to the bottom ply 12 of the inflatable fabric member 9.

In order to form a satisfactory anchorage for the flanged portion 18 of the piece of fabric 14 forming the sleeve 10, a reinforcement element 22 of annular form is cut from a flat piece of fabric. The reinforcement 22 is adapted to overlay completely the several tabs 19 comprising the flanged portion 18 and to project therebeyond so as to enable it to be secured to the top fabric ply 11 of the inflatable fabric member 9. A similar reinforcement 23 is applied to the several tabs 21 of the flange portion 20 to secure them in place with respect to the bottom fabric member 9 and a circular fabric cover patch 24 is arranged to overlay the whole assembly.

The flange portion 7 of the valve 2 is secured in place over the reinforcement 22 with the bore 5 thereof in coaxial relation to the sleeve 10. A patch 24 of annular shape is cut from a flat piece of fabric so as to encircle the base of the stem portion 6 of the valve 2. The patch 24 is arranged to overlay the uppermost surface of the flange portion 7 of the valve 2 and extend therebeyond. The patch 24 is thus enabled to be adhesively secured to the top fabric ply 11 of the inflatable fabric member 9 as shown in Fig. 2.

In order that fluid under pressure introduced to the bore 5 of the valve 2 of the inflating means 1 may be distributed through the entire inner chamber 26 of the inflatable fabric member 9, a number of apertures 27 are provided in the fabric 14 comprising the sleeve 10. It will be noted that the inflating means 1 comprising the valve 2 and the sleeve 10 affords a highly advantageous means

of introducing the inflating fluid under pressure to the chamber 26 in the inflatable fabric member 9 and at the same time provides a reinforcement for the aperture 8. Moreover, the inflating means 1 is sufficiently flexible to promote the readily collapsible character of the inflatable fabric member essential in the many varied forms of products such as those previously mentioned.

While certain representative embodiments and details have been shown for the purpose of illustrating the invention, it will be apparent to those skilled in this art that various changes and modifications may be made therein without departing from the spirit or scope of the invention.

15 I claim:

1. In an inflatable fabric member embodying two fabric plies having a fluid impervious coating thereon disposed in opposed relation to each other and joined together by a plurality of substantially inextensible tie threads woven at least partially into each of the fabric plies, the marginal edges of said fabric plies being sealed to define a substantially fluid-tight chamber therebetween, an inflating means comprising an open-ended flexible walled conduit extending between the fabric plies and having at least one aperture in the wall thereof communicating with the chamber; a port mounted on one of the fabric plies and operatively connected to an end of the conduit for admitting fluid under pressure to the chamber; and means on the other fabric ply for closing the other end of the conduit.

2. In an inflatable fabric member embodying two fabric plies having a fluid impervious coating thereon disposed in opposed relation to each other and joined together by a plurality of substantially inextensible tie threads woven at least partially into each of the fabric plies, the marginal edges of said fabric plies being sealed to define a substantially fluid-tight chamber therebetween, an inflating means comprising a valve having a base portion thereon; a conduit disposed between the fabric plies in substantially coaxial relation to the valve, said conduit being formed of flexible material and having a plurality of apertures therein communicating with the chamber; means for mounting the valve on one ply of fabric; and means on the other ply of fabric for closing the end of the conduit opposite the valve.

3. In an inflatable fabric member embodying two fabric plies having a fluid impervious coating thereon disposed in opposed relation to each other and joined together by a plurality of substantially inextensible tie threads woven at least partially into each of the fabric plies, the marginal edges of said fabric plies being sealed to define a substantially fluid-tight chamber therebetween, an inflating means comprising a conduit disposed between the fabric plies, said conduit being formed of a strip of fabric and having at least one aperture in the wall thereof communicating with the chamber; a port having a base portion thereon, said port admitting fluid under pressure to the conduit; means for mounting the port on the fabric ply at one end of the conduit; and means on the other fabric ply for closing the other end of the conduit.

4. In an inflatable fabric member embodying two fabric plies having a fluid impervious coating thereon disposed in opposed relation to each other and joined together by a plurality of substantially inextensible tie threads woven at least partially into each of the fabric plies, the marginal edges of said fabric plies being sealed to define a sub-

stantially fluid-tight chamber therebetween, an inflating means comprising a fabric tubular element disposed between the fabric plies, said element having a plurality of apertures formed in the wall thereof; a valve having the base thereof mounted on one of the fabric plies substantially in registration with an end of the fabric element; means for sealing the base of the valve with respect to the ply of fabric on which it is mounted; and means providing a fluid-tight closure for the end of the tubular element opposite that to which the valve is connected.

5. In an inflatable fabric member embodying two fabric plies having a fluid impervious coating thereon disposed in opposed relation to each other and joined together by a plurality of substantially inextensible tie threads woven at least partially into each of the fabric plies, the marginal edges of said fabric plies being sealed to define a substantially fluid-tight chamber therebetween, an inflating means comprising a generally tubular element the wall of which is formed of a flat piece of single-ply fabric joined at its ends disposed between and secured at its open ends to the fabric plies of the inflatable member to reinforce an aperture therein and to define a conduit therebetween, said element having a plurality of openings formed in the wall thereof for communication with the chamber; a valve mounted on one of the fabric plies, said conduit being connected with the conduit and closing one end thereof; and means forming a fluid-tight closure for the end of the conduit opposite the valve.

6. In an inflatable fabric member embodying two fabric plies having a fluid impervious coating thereon disposed in opposed relation to each other

and joined together by a plurality of substantially inextensible tie threads woven at least partially into each of the fabric plies, the marginal edges of said fabric plies being sealed to define a substantially fluid-tight chamber therebetween, an inflating means comprising a generally tubular element the wall of which is formed of a flat piece of single-ply fabric joined at its ends disposed between and secured at its open ends to the fabric plies of the inflatable member to reinforce an aperture therein and to define a conduit therebetween, said element having a plurality of openings formed in the wall thereof for communication with the chamber; a flanged portion adjacent the open ends of the tubular element for attachment to each of the fabric plies of the inflatable member; an annular sealing member securing the flanged portion to the fabric plies; a valve mounted on one of the fabric plies with its base in substantial registration with an end of the tubular element; an annular sealing member encompassing the base of the valve and secured in place over the flanged portion of the tubular element and its sealing member; and a fabric patch secured to the other fabric ply closing and sealing the end of the tubular element opposite the valve.
